UNITED STATES PATENT OFFICE.

JAMES SPRUCE, OF WATERBURY, CONNECTICUT, ASSIGNOR TO THE
SCOVILL MANUFACTURING COMPANY, OF SAME PLACE.

IMPROVEMENT IN BUCKLES.

Specification forming part of Letters Patent No. 150,368, dated April 28, 1874; application filed
March 26, 1874.

To all whom it may concern:

Be it known that I, JAMES SPRUCE, of Waterbury, in the county of New Haven and State of Connecticut, have invented a new Improvement in Buckles; and I do hereby declare the following, when taken in connection with the accompanying drawings and the letters of reference marked thereon, to be a full, clear, and exact description of the same, and which said drawings constitute part of this specification, and represent, in—

Figure 1 a view of the buckle complete. Figs. 2, 3, 4, and 5 the parts detached; Fig. 6, a central section; and in Fig. 7, the three parts as arranged preparatory to closing the sleeve thereon.

This invention relates to an improvement in the construction of that class of buckles designed especially for fastening or adjusting wearing-apparel, and particularly those which are provided with a loop by which to attach the fixed end of the strap or band; and the invention consists in forming the frame, loop, and tongues from separate pieces, and uniting these three parts by a sleeve, which not only unites the parts but forms the hinge upon which they turn.

A is the frame, *a a* the tongues, and B the loop. These parts are, preferably, made from wire bent into the form substantially as seen in Figs. 2, 3, and 4, one side of the frame open, as at *d*, and the base *b* of the tongues corresponding to the recess *d* in the frame, so as

to lie therein, as seen in Fig. 7. The loop B is bent into shape, as seen in Fig. 4, so that the two ends will meet upon one side. This is placed the open side at the base of the tongues, as seen in Fig. 7. In this condition the parts are secured together by an encircling sleeve or band, *e*, as seen in Figs. 1 and 6. This sleeve is preferably made from thin sheet metal, perforated as at *i i*, corresponding to the tongues *a a*, and set over the tongues, then closed around the base of the tongues, the open side of the frame, and corresponding side of the loop; but separate bands may be used at different points to secure the parts together. As the points of connection are round, they will turn independent of each other, the sleeve or bands forming the hinge.

It is not essential that the base of the tongues lies in the recess or opening in the side of the frame, as it may lie over one of the parts or between the two. I prefer, however, to arrange the parts as first described.

I claim as my invention—

The herein-described buckle, consisting of the frame A, the tongues *a a*, formed with the base *b* and the loop B, the said three parts united and hinged together by a sleeve or bands, *e*, substantially as specified.

JAMES SPRUCE.
